INVENTOR

R.E. Wiss

BY *Victor J. Evans*

ATTORNEY

WITNESS:

UNITED STATES PATENT OFFICE.

ANDREW HALVORSON, OF FRANKLIN, MINNESOTA.

CAP TOOL.

Application filed July 29, 1925. Serial No. 46,848.

This invention relates to a tool, the object of the invention being to press the flange on a fruit-jar cover against the rubber gasket so as to make a tight joint.

5 This invention also consists in certain other features of construction and in the combination and arrangement of the several parts, to be hereinafter fully described, illustrated in the accompanying drawings, and 10 specifically pointed out in the appended claim.

In describing my invention in detail, reference will be had to the accompanying drawings wherein like characters denote like 15 or corresponding parts throughout the several views, and in which:—

Fig. 1 is a sectional view through a jar and its cap and showing the invention in use,

20 Fig. 2 is a view of the device itself, and Fig. 3 is a section taken through line 3—3 of Fig. 1.

As shown in these views, the device is formed of heavy wire bent intermediate its 25 ends into U-shape to provide a handle part 2, one limb having an extension thereon which is bent into semicircular form to provide a jaw part 1, the end of the other limb of the U-shaped part being twisted around the 30 first limb at the junction of the jaw part with said first limb, and the extremity of the twisted part being bent into U-shape with the free limb of this U-shaped part forming a lip 3. The jaw part 1 is placed in 35 engagement with the bottom groove in the

neck of the jar, as shown in Fig. 1 and then the device is rotated, so that the lip 3 will press upon the flange at the bottom of the cap and flatten the same upon the rubber gasket so as to make a tight fit between the 40 cap and jar. This device will take out kinks and bent places in the flange of the cap so that old covers can be used over and over again.

It is thought from the foregoing description that the advantages and novel features 45 of my invention will be readily apparent.

I desire it to be understood that I may make changes in the construction and in the combination and arrangement of the several parts, provided that such changes fall 50 within the scope of the appended claim.

What I claim is:—

A jar-cap removing tool comprising a strip of heavy wire bent intermediate its ends 55 into U-shape to provide a handle part, an extension on one limb of the U-shaped handle part bent into semicircular form to provide a jaw, the end of the other limb of the U-shaped part being twisted around the 60 first limb at the junction of the jaw part with said first limb, and the extremity of the twisted part being bent into U-shape, with the free limb of this U-shaped part forming 65 a lip, the jaw part being arranged to engage the bottom groove in the neck of a jar with the lip engaging the flange of a cap placed on the jar.

In testimony whereof I affix my signature.

ANDREW HALVORSON.
